E. W. DRIEMEYER

LOCK FOR LAMP DOORS

Filed March 25, 1920

INVENTOR:

Edward W. Driemeyer,

84

Arthur T. Ewold

ATTORNEY.

UNITED STATES PATENT OFFICE.

EDWARD W. DRIEMEYER, OF CINCINNATI, OHIO, ASSIGNOR TO THE K-D LAMP COMPANY, OF CINCINNATI, OHIO, A CORPORATION OF OHIO.

LOCK FOR LAMP DOORS.

Application filed March 25, 1920. Serial No. 368,683.

To all whom it may concern:

Be it known that I, EDWARD W. DRIEMEYER, a citizen of the United States, and resident of Cincinnati, in the county of Hamilton and State of Ohio, have invented a certain new and useful Improvement in Locks for Lamp Doors, of which the following is a full, clear, and exact description, reference being had to the accompanying drawings, forming a part of this specification.

The present invention relates to locks for lamp doors and particularly to such as are designed for use on automobile headlamps.

By reason of the continual vibration and shock to which the headlamps of automobiles are subjected, the doors, containing the front lenses or glasses, frequently become loosened and are broken or lost. It is to the provision of a simple and efficient lock, whereby the difficulties mentioned are overcome, that the present invention is directed.

A further object of the invention is to provide a lock for a lamp closure, of neat and unobtrusive appearance, so as not to detract from the design and outline of the lamp itself.

Other objects of the invention will appear from the following detailed description thereof.

In the drawings:

Figure 1 is a front view of a headlamp equipped with a lock constructed in accordance with the present invention, parts being broken away;

Figure 2 is a top view of said lamp;

Figure 3 is a perspective of a portion of the lock.

The numeral 1 indicates the casing of an ordinary headlamp. The front of said casing is provided with an annular flange 2, over which the flange 3 of the closure frame 4 is adapted to fit in the usual manner. The flange 2 is provided with a plurality of slots 5, preferably four in number. The slots 5, as indicated in Figure 3 are angularly disposed with reference to the front edge of the flange 2, the angle of inclination being uniform in all of the slots. The flange 2, in front of the slots 5, is provided with bent-in portions or depressions

6; these depressions or grooves are disposed so as to communicate with the ends of the slots nearest the front edge of the flange.

The flange 3 of the closure frame is provided with a plurality of pins or studs 7, having external heads 8. The pins 7 are arranged to pass through the grooves 6 and upon rotation of the closure upon the flange 2 to enter the slots 5. The front edges of the slots acting against the pins 7 during the rotation of the closure draw the closure tightly against the front edge of the flange 2.

The body of the lamp has riveted thereto a spring clip 9, which extends over the flange 2, at an elevation just sufficient to permit the entry of the flange 3 of the closure frame 4. The clip 9 is provided furthermore with a perforation 10, which is disposed over the rear end of one of the slots 5, so that when the closure is placed on the lamp and rotated to position as above indicated, one of the heads 8 will engage in the perforation 10 of the spring clip, to lock the closure upon the lamp.

From the foregoing description the nature and advantage of the present invention will be apparent to those skilled in the art to which the same appertains. When the closure is placed on the lamp and rotated into position, the head 8 of one of the lock pins 7 enters the perforation 10 of the clip which immediately springs downwardly over the same, effectually locking the closure against rotation, and thus against removal from the lamp. It will be seen thus, that by reason of the several features of construction above described, a simple, neat and efficient lock is provided, whereby the removal and loss of the closure is absolutely prevented. The mechanism described being simple in construction it will be understood furthermore that the same is extremely inexpensive in manufacture as well in its application to the lamps.

Having thus fully described my invention, what I claim as new and desire to secure by Letters Patent, is:

A lock for lamp closures comprising the combination with a body having a flange provided with slots angularly disposed with reference to the front edge of said flange,

grooves between the front edge of said flange and the ends of the slots nearest said edge, and a closure having a flange arranged to fit around the outer circumference of the body flange, of lock pins in the closure flange, the inner ends of said pins being arranged to pass through said grooves into slots and to draw said closure against the front edge of said body flange upon rotation

of the former upon the latter, external heads 10 on said lock pins, and a spring clip on the body of said lamp, said clip having a perforation arranged to engage one of said heads when the closure is rotated so that the pins are in the extreme ends of the slots 15 away from said grooves, to secure the closure against rotation.

EDWARD W. DRIEMEYER.
